(57) **CLAIM**

The ornamental design for a blind hole mount, as shown and
described.

DESCRIPTION

FIG. 1 is a perspective view of the clip portion of the blind
hole mount of FIG. 6, the clip portion removed for ease of
illustration;

FIG. 2 is a front elevation view thereof, the rear elevation
view being identical thereto;

FIG. 3 is a right side elevation view thereof, the left side
elevation view being identical thereto;

FIG. 4 is a top plan view thereof;

FIG. 5 is a bottom plan view thereof;

FIG. 6 is an exploded perspective view of the blind hole
mount, the blind hole mount comprised of a base portion and
a clip portion;

FIG. 7 is a perspective view of the blind hole mount;

FIG. 8 is a front elevation view thereof, the rear elevation
view being identical thereto;

FIG. 9 is a right side elevation view thereof, the left side
elevation view being identical thereto;

FIG. 10 is a top plan view thereof; and,

FIG. 11 is a bottom plan view thereof.

The broken lines are for the purpose of illustrating the
environment of the article only and form no part of the
claimed design.

1 Claim, 3 Drawing Sheets
